[57] **CLAIM**

The ornamental design for a lock housing with connecting mechanisms, as shown and described.

DESCRIPTION

FIG. 1 is an exploded perspective view showing a lock housing with connecting mechanisms according to my new design;

FIG. 2 is a longitudinal sectional view through the assembled mechanisms in completely assembled position;

FIG. 3 is a perspective view taken from the top, front and right side of one of the connecting mechanisms;

FIG. 4 is a right side elevational view thereof;

FIG. 5 is a top plan view thereof;

FIG. 6 is a bottom plan view thereof;

FIG. 7 is a left end view thereof;

FIG. 4

FIG. 5

FIG. 6

FIG. 7
